UNITED STATES PATENT OFFICE.

HARRY D. POMEROY, HAROLD T. AVERY, AND RAY M. WHEELER, OF SYRACUSE, NEW YORK.

DISK-RECORD CABINET.

1,360,679.

Specification of Letters Patent. Patented Nov. 30, 1920.

Application filed April 24, 1920. Serial No. 376,332.

To all whom it may concern:

Be it known that we, HARRY D. POMEROY, HAROLD T. AVERY, and RAY M. WHEELER, citizens of the United States, residing at 5 Syracuse, in the county of Onondaga and State of New York, have invented certain new and useful Improvements in Disk-Record Cabinets, of which the following is a specification:

10 This invention relates to improvements in record cabinets, designed for filing the disk records of phonographs, talking machines, and the like, and has for its object to provide a novel and simple cabinet construction, wherein a large number of disk records of different sizes may be compactly filed, and wherein each record is provided with a numbered compartment for identifying the record. A further object is to provide novel, 15 simple and effective means for selecting and also for ejecting any record of a series. And a further object is to generally improve and simplify the construction, arrangement and operation of record filing cabinets.

20 We attain these objects by the means set forth in the detailed description which follows, and as illustrated by the accompanying drawings, in which—

Figure 1 is a front end elevational and partial vertical section; Fig. 2 is a vertical longitudinal section, taken on line 2—2 of Fig. 1. Fig. 3 is a vertical cross-section, taken on line 3—3 of Fig. 2. Fig. 4 is a horizontal section, substantially on line 4—4 of Fig. 2. Fig. 5 is an enlarged sectional view of the selective gearing. And Fig. 6 is an enlarged fragmentary plan view of the bearing which supports the gearing.

In the drawings, 2 designates generally 40 the cabinet, comprising the top 2', sides 2^a, back 2^b, and bottom 2^c. The front end of the cabinet is normally open. Within the cabinet is a horizontal platform 3, upon which the disk records 4 and 4' are supported by 45 gravity. This platform is disposed a short distance above and parallel to the bottom 2^c, and consists of alternate narrow strips of wood 3', and slightly broader but thinner strips of sheet fiber 3^a, all of said strips being 50 perforated to receive common supporting rods 3^c, whose opposite ends are preferably supported by the side walls 2^a. The disks 4 and 4' rest upon the laminations 3'

and are suitably spaced from each other by the laminations 3^a. Above the platform 3^a the disks are further and regularly separated by angular spacers of thin fiber or like material 5 of the same thickness as the strips 3^a, the reduced forward ends of which are inserted between the layers 3' of the platform, 60 and are held rigidly in place, and in line with the strips 3^a, by one of the rods 3^c. The enlarged rear ends of the guards 5 are supported by similar transverse parallel bars 6, which are preferably grooved to receive the 65 guards, and the latter may be made rigid by means of glue or cement, in the usual manner. By constructing and disposing the guards 5, as herein shown, the disks are evenly spaced and prevented from rubbing 70 or chafing each other, and owing to the peculiar shape of the guards but little material is required in their construction. By extending the forwardly inclining ends of the guards to the front of the cabinet, the records 75 are more readily and quickly inserted in their compartments than if the guards stood vertically. 7 represents a common stop consisting of a rod which is driven transversely through the top edges of the spacers 3^a, for 80 preventing the accidental escape of the disks from the cabinet, as shown in Figs. 1 and 2. Each record compartment comprising the space between the adjacent guards 5, is given 85 a number, as indicated by the staggered rows of numerals shown near the bottom in Fig. 1. Each disk 4 is also provided with a corresponding number (not shown), which may refer to the title or name of the record. For 90 example, disk number 1 may contain the record of "The Mocking-Bird," and should always be placed in compartment 1 of the cabinet, and so on, throughout the list of records. At the rear of each disk receiving 95 compartment is disposed a vertically arranged ejecting lever or kicker 8. These levers are all substantially the same size and shape, and they are all pivotally mounted on a common transverse shaft 8', which may be anchored in the sides 2^a, in a well-known 100 manner. The bottom ends of the levers 8 substantially fill the space between the sides 2^a, as shown in Figs. 3 and 4, for preventing the accidental shifting of the levers out of line with the corresponding records. The 105 levers 8 preferably taper from the shaft 8'

toward their free upper ends sufficiently to allow them to move freely between the guards 5 during the ejecting operations. By this construction the guards tend to keep all 5 of the levers 8 in line with the disks. As each record is inserted in its compartment, it forces the corresponding kicker 8 backward, as from the dotted to the full line position shown in Fig. 2, and holds it there 10 until the next ejecting operation. The ejecting movements of the several levers 8 are effected by a common rod 9 of peculiar shape, which is disposed longitudinally between the bottom 2^c and the platform 3, and is pivoted 15 in bearings 10, 11 and 12'. The bearing 12' is positioned at the middle of an angular plate 12, which faces the lower front portion of the cabinet, the said plate having a vertical portion 12^a upon which is inscribed 20 the compartment numbers, as described, and having a horizontal portion 12^b, which is provided with a square window or opening 12^c directly over the rod 9. The rear end 25 of the rod 9 is bent upwardly and then forwardly to provide a horizontal striker 9^b, which is adapted to register with the several levers 8 when said rod is rocked in opposite directions, as shown in Fig. 3. The forward end of rod 9 is fitted with a head or knob 9^c, 30 by means of which said rod may be pulled outwardly for ejecting a record (see dotted lines in Fig. 2). The head 9^c is preferably swiveled to the rod 9, so as to prevent the operator from accidentally rocking said rod 35 and thereby disturbing the proper selection of the records. A spring 9^a is interposed between the bearing 10 and the upright portion 9^a, and exerts its tension for restoring rod 9 to its normal idle position, shown by full 40 lines in Fig. 2, ready for the next ejecting operation.

The selection of any desired record is accomplished by means of a rotary dial 13, which contains numbers corresponding to 45 the numerical index 12^a and the records. This dial is disposed horizontally beneath the platform 3, and the edge of the dial is knurled to facilitate its operation manually. The numbers on the dial 13 are preferably disposed in a circle, so that the numbers may be successively brought into register with the window 12^c. The dial 13 is mounted upon the hub 14' of a bevel gear 14, the said hub being squared and fitting a 50 square hole in the dial, and a screw 13' is threaded into the hub for holding the parts in place. The gear 14 is journaled in the top portion of the bearing 11, and meshes with and drives a similar gear 15, which is 55 keyed to the rod 9 by a key 15' that plays in a groove 9^e of the rod (see Fig. 5). The gear 15 rocks the rod 9, but the latter is slideable in said gear during the ejecting operations, as shown by dotted lines in Fig. 2. 60 The gear 15 is held in the proper position

by a sleeve 15^a. The hub of the gear 14 is also provided with a sleeve 14^a, which aids the hub in supporting the dial 13. The rod 9 is rocked in opposite directions, as indicated by the dotted lines in Fig. 3 alone by 50 the dial 13 and gears 14 and 15, for positioning the striker 9^b directly behind the ejecting levers 8, which correspond to the record numbers shown through the window 12^c, as for example, the number 14 (see Figs. 75 1, 3 and 4), which indicates the compartment, as well as the corresponding ejecting lever 8 for the record 14. We have shown records of two sizes, 4 and 4'. Both of 80 these sizes may be stored in our cabinet without any change, and the smaller records may be selected and expelled in the same manner as the larger ones, without necessitating any change or any extra work. The levers 8 when moved forwardly for expelling the records are stopped by a common transverse rod 8^a, which extends through the cabinet 85 (see Fig. 2).

When a particular record is wanted, the operator first ascertains the number of said 90 record, and then manipulates the dial 13 in the proper direction for bringing that number opposite the window 12^c, where he leaves the dial. This rotation of the dial 13, operates the gears 14 and 15, and rocks the 95 rod 9 for positioning the striker 9^b in register with the proper record. The operator then pulls outwardly on the rod 9, which causes the striker 9^b to actuate the proper lever 8 for expelling the record. After a 100 record is removed from the cabinet, the rod 9 is drawn inwardly by the spring 9^a, while the lever 8 remains in the operated position until the record is replaced, and during the final inward movement of the record, the latter restores the operated lever 8 to 105 the full line position shown in Fig. 2.

Having thus described our invention, what we claim as new and desire to secure by Letters Patent, is—

1. A record cabinet comprising a platform having a plurality of grooves adapted to be numbered for supporting disk records by gravity, angular guards partially supported by said platform, an ejecting lever alining with each of said grooves and movable between adjacent guards, a rockable member having a striker adapted to be brought into register with the several levers by the rocking of said member, bearings in which said member slides during the expelling of the records, and a dial adapted to contain numerals corresponding to the numbers of said grooves adapted to be rotated manually for rocking said member. 115

2. A disk record cabinet, including a grooved platform adapted to support a plurality of disk records, a plurality of angular guards partially supported by said platform for spacing said records, a plurality 120

of ejecting levers disposed vertically between said guards and movable forwardly in vertical planes for ejecting the records, an ejecting rod provided with a horizontal striker 5 adapted to be rocked in opposite directions for bringing said striker into registry with said levers, said rod adapted to be pulled outwardly manually for actuating said levers, tension means for moving said rod in

the opposite directions, gears for rocking 10 said rod, and a manually rotatable dial for driving said gears.

In testimony whereof we affix our signatures.

HARRY D. POMEROY.
